C. LADD-DAVIS

AUTOMATIC FIRE EXTINGUISHER FOR DISTRIBUTING AQUEOUS LIKE FLUENT MATERIAL

Original Filed March 25, 1913

UNITED STATES PATENT OFFICE.

CLARENCE LADD-DAVIS, OF BROOKLYN, NEW YORK, ASSIGNOR TO HIMSELF, AND JAMES A. TAYLOR, JOINT TRUSTEES, OF BROOKLYN, NEW YORK.

AUTOMATIC FIRE EXTINGUISHER FOR DISTRIBUTING AQUEOUS-LIKE FLUENT MATERIAL.

Refiling of application Serial No. 756,688, filed March 25, 1913. This application filed July 28, 1919. Serial No. 313,927.

To all whom it may concern:

Be it known that I, CLARENCE LADD-DAVIS, a citizen of the United States, residing at the borough of Brooklyn, in the county of 5 Kings and city and State of New York, have invented certain new and useful Improvements in Automatic Fire Extinguishers for Distributing Aqueous-Like Fluent Material, of which the following is a specification.

The device shown, described and claimed herein, is a modification of the particular type of automatic fire extinguishers shown and broadly claimed in my co-pending application Serial No. 313,926, filed July 28, 1919, of even date herewith, and shows an application of the broad principle shown, described and claimed in said aforesaid application No. 313,926, which is applicable so far as such broad principles are concerned for use with both finely comminuted solid materials, and with liquids also; the particular device herein shown, described and claimed, while not limited strictly, especially 25 in the broad claims hereof, thereto, being particularly designed, and especially adapted for use in distributing upon the adjacent fire zone a fluidal fire-extinguishing material of liquid and watery form; upon the 30 thermal actuation of a suitable thermo-trip, the release of which (usually when the surrounding temperature reaches 155 degrees Fahrenheit) causes expulsion of the liquid in a forcible manner, by reason of the pendulous, rotative, nutative, and gyratory movements which the device performs upon 35 such release; such expulsion being practically uniform thruout all dimensions of space, whereby the adjacent floor and ceiling, (and if the apartment be small, the walls also) will have every portion of their surfaces wetted with the fire extinguishing liquid; which may be of any kind, such for instance as carbon tetrachloride (CCl₄), 40 solutions containing the same, or any liquid aqueous like fluent material carrying fire-killing gases or like granulated solids held in suspension; including those forming a blanketing foam when projected into the fire-zone; all which I hold to be within the 45 meaning and scope of the words: "liquid

aqueous-like fluent material," wherever I have used the same in the description or the claims hereof that will extinguish fire.

My said invention is fully shown and set forth in the following specification, of which the accompanying drawing forms a part, wherein similar letters or numerals of reference designate like or equivalent parts, wherever found thruout the several views, 55 and in which:

Figure 1 is a side view, partially in section, of the supporting frame and receptacle for containing the liquid.

Figure 2 is a top-view of the bottom portion of the same, also in section on the line *a—a* of Figure 1, the motor-spring being shown in full lines.

Figure 3 is a front face view in detail of one of the delivery nozzles of the device, 70 showing the closure carrying ring and closure-stopper in the open and liquid delivering position.

Figure 4 is a top view in detail, taken in horizontal section on the line *b—b* of Figure 1, of the combined air-inlet and filling orifice, its nozzle and stopper.

Figure 5 is a top view of the motor-spring winding ratchet mechanism, taken in horizontal section on the line *c—c* of Fig. 1.

Figure 6 is a top-plan view, partially in section of the form of outlet nozzle I prefer to use; dotted lines showing same in open position.

Figure 7 is a view in detail looking from 85 one side of Fig. 1, of the combined motor-spring ratchet, etc., and trip-cable fork; and

Fig. 8 shows the support on a reduced scale, the vibratory arcuate path traversed by the frame and included rotating receptacle 90 upon the release of the thermo-trip being indicated by the dotted line.

Referring to the drawing:

The reference letter A designates the gyroscopic-frame, revolvably supported in 95 which is the receptacle B. The frame A is usually formed of metal cast or drop-forged into proper form, and save for minor differences is essentially the same as the like frame shown and described in my before 100 mentioned co-pending generic application. The liquid receptacle B is preferably of the

frustro-conical form indicated in Fig. 1, and formed of suitable sheet metal. For convenience of assembling, as hereinafter more fully described, the top-plate and the annular wall are usually formed integral, and the bottom-plate is secured to the annular wall 7 by any suitable liquid tight joint, many of which are well known in the art.

As shown in Figs. 1 and 2, the bottom-plate of the receptacle is dished inward at the center so as to form a cylindrical chamber to receive the coil-motor-spring E. Fitting in this cylindrical chamber is the supporting-spider D', composed of the top-plate 150', having the central boss 108, (Fig. 1), and the standards 151, extending at a right angle to 150', from which extend radially outward, (Figs. 1 and 2) the receptacle supporting spider-arms 66, ending in the upturned closure-ring securing lugs 110 (Figs. 1 and 2) the office of which is to hold the annular closure-carrying-ring 5', in position upon the receptacle so as to be capable of vibration thereon.

The spider-arm or bar 66, (on the side which is at the left of Fig. 1) is provided with a depending lug or lock-fin 66', which abuts against the upper end of the rocking-trip-lever 67, of the thermo-trip, the securing-main-plate 60 of which is secured on what in Fig. 1, is the rear side of the bottom-bar of the frame by screws passing into the same at the points indicated by 67', though in the drawing in Fig. 1 the frame A, and such main-plate are both partially broken away, in order to show how the trip-lever 67, rests against a rock knife-edged-lug 69, at the rear of a slot open toward what is the left of Fig. 1. Such trip-lever is secured in such slot by an easily fusible solder usually that used in fire-extinguishing apparatus for their thermo-trips, which melts at about 155° F.) which solder in order to more clearly show the construction, is in the drawing not shown. To the lower end of such rocking-trip-lever 67, is firmly secured in any desired manner the end of the secondary supporting trip-cable 70, a loop of which is secured to the rocking trip-lever a short distance above the lower end by the same easily fusible solder, as indicated at 63; which releasing first adds a thrust of greater power to the trip-lever as the device falls upon the melting of both solders. However, as I do not claim such trip specifically herein even in combination, the same having been so claimed in my co-pending generic application herein referred to, I have not deemed it essential to more specifically show or describe such thermo-trip G herein, nor several other parts.

The receptacle B is pivotally supported in the frame A by suitable pivot-pins 37 and 51, co-acting with suitable bearings 105 and 106, secured in position in the top and bot-

tom plates in any desired manner, usually by the screw-nut 167, and the boss 108 of the spider D', the joints thereof with the top and bottom plates of the receptacle being of course made liquid tight, in any suitable manner; and in order to lessen friction the bearings are usually provided with sleeves and washers of any suitable anti-friction material, such as plumbago composition, located at proper points, as clearly indicated in Fig. 1.

The lower pivot-pin 37 is formed integral with the motor-spring shaft F, while the upper pivot-pin 51, with an enlarged upper portion 52' which may be formed integral therewith, or which may (as shown in Fig. 1) be in the form of a sleeve having the upper flange 54, such sleeve being secured to 51 by the drive-pin 52, and held against removal from the frame A by the securing-pin 53'; the purpose of 52' being to act as a protective dust cover for the upper bearing 105 when in position, and when withdrawn with the pin 51, to leave sufficient space between the top of the receptacle and the top-bar of the frame A, to permit the receptacle to be slipped sideways into the frame over the upwardly extending square drive-stud 112, of the pawl-carrying-plate 113, of the motor-spring winding mechanism, and dropped back into the winding position with such drive-stud 112 located in the like shaped cavity formed to receive it in the lower end of the motor-spring shaft F.

The coil motor-spring E is secured at the inner end to the motor-spring shaft F, by a screw or stud 36' passing thru a suitable slot formed in the spring, and the outer end is slotted so as to slip over a securing-stud 36 on the side-bar 151 of the supporting-spider D'; which stud 36 is so shaped as to slip out of the slot when the spring has reached the limit of its unwinding; the outer end thereof being curved inward at 155 (Fig. 2) and so shaped that when so released its own resiliency will force it into the position shown in dotted lines, with such curved end portion in contact with the next inward coil. When the motor-spring and its shaft are placed in position in the motor spring chamber, a split-plate 109, (Fig. 1) is used to close such chamber against dust, which is secured in place by screws 109'; and revolubly mounted in such plate 109, and in the circular top-plate 150' of the supporting-spider D' in suitable journal-boxes (not shown) formed therein, and located adjacent to the peripheral wall of the spring-chamber, are a plurality of anti-friction rollers 150, with which the outer coil of the spring contacts when unwound and released, so as to keep the spring out of contact with the walls of the spring chamber, and the securing stud 36, thus permitting the receptacle to thereafter continue in rotation by its 130

own inertia; the curved end portion 155 of the motor-spring causing the rollers to ride easily thereover. By this construction the time of rotation of the receptacle will be materially increased.

Of course it is understood that the drawing of the motor-spring E is intended to be only diagrammatic, and that in practice the same has a much larger number of coils than are shown; and that the rollers 150 are of sufficient diameter to keep the spring from rubbing against the securing-stud 36, when once released therefrom, although in Fig. 2 such stud is shown somewhat exaggerated in length.

Revolutely mounted in a cavity formed to receive it in the central enlarged boss-portion 120 at the center of the bottom-bar of the gyroscopic-frame A, is the motor-spring winding-ratchet mechanism, comprising the upper pawl carrying-plate 113, the cylindrical journal portion 114, and the square shaped drive-studs 116, and 112, all formed of one piece of metal. The cavity in the inner side of the boss is provided with the ratchet-cavities 121 at the periphery, to receive the outer ends of the spring actuated pawl-bolts 119 reciprocating in suitable chambers formed in the pawl-carrying-plate (Figs. 1 and 5). The lower end of the motor-spring-shaft F is sufficiently large of diameter to cover and conceal the plate 113, and thus protect the ratchet mechanism from dust, and is provided with a central cavity to receive the drive-stud 112, so that rotation of the plate 113 will rotate such shaft F, and thus wind up the spring E, when such plate is rotated by the combined turn-nut and trip-cable fork 118, secured upon the bottom drive-stud 116 by the drive-pin 117 (Fig. 1); and after the motor-spring has been fully wound up the ratchet-plate may be further locked against movement by a set-screw 122, (Fig. 5) in order that the contact of the secondary trip-cable 70 (Fig. 8) with the fork of the turn-nut when the device is suspended, may not further rotate the same. Such fork is preferable to a ring in that it allows of quicker release of the trip-cable from the frame upon the actuation of the thermo-trip, while at the same time acting equally well to hold the device in position ready to be actuated.

During the winding up of the motor-spring the receptacle B is locked against rotation in the gyroscopic-frame A by the force of the spring exerted upon the lug 36 of the supporting-spider D', by the contact of the lock-fin or lug 66' of such spider with the upper end of the rocking-lever 67 of the thermo-trip "G," which is usually of the fusible solder form, which upon the surrounding atmosphere reaching the required temperature, will automatically release the mechanism so as to cause rotation of the

receptacle within the frame, and simultaneous vibration upon the main support.

In any event, upon the thermal release of the thermo-trip, the rocking trip-lever 67, will be wholly drawn away and out of contact with the receptacle and frame, and left suspended in the position shown in dotted lines in Fig. 8 in the secondary support 70', the trip-cable 70 being for that purpose provided with a suitable end weight and center stop, as clearly indicated in such Fig. 8.

Surrounding the receptacle at the base is the closure carrying-ring 5' kept spaced outward therefrom by the slip-springs 111 (Fig. 2), thru orifices 129 in which ring project outwardly the delivery nozzles 126, thru which the fire-extinguishing liquid material is ejected; and secured to such ring 5' by rivets 132 and projecting out thru the orifices 129 are the stopper carrying-springs 131, each carrying at its outer end a closure-stopper 130, which normally closes (Figs. 2 and 6) the substantially circular or cylindrical outlet orifice 127 in the nozzle 126, which is usually in the form of a cap screwed on the outer end of the delivery-pipes 123 and 123', which preferably pass thru an angular sleeve 125 provided with the inner flange 124. The joints between such flange and the receptacle wall 7, and the exterior of the outlet pipes are usually made liquid tight by soldering; and a suitable washer 128 (Fig. 6) is usually interposed between the outer end of the sleeve 125 and the inner end of the nozzle-cap.

The stopper-carrying springs 131 are each provided with a nozzle-slot 129', (Figs. 3 and 6) so that when the closure carrying-ring 5' is vibrated to the left (as indicated by the arrow in Fig. 6), the springs will be forced by their own resiliency back into the position shown in dotted lines, with the nozzles projecting out thru the slots and with their outlet orifices uncovered, so as to permit of free flow of the liquid therethru. The closure carrying-ring 5' is preferably held against accidental upward displacement by having the upward extensions 110 of the supporting spider D' bent slightly inward at the top after the insertion of the ring in place, as clearly shown in Fig. 1.

So far as ejection of the liquid is concerned, the outlet pipes might just as well be merely short nozzles ending just within the receptacle wall, to the inner ends of which the liquid will be directed by the deflecting-vanes 95 and 95' upon the rotation of the receptacle, but in order to prevent leakage thru such outlets during the long period during which the device will ordinarily be suspended in position ready for use, and also to prevent permanent sealing of the stoppers to the outlet orifices by possible corrosion, or chemical action of the contained liquid, which would render the

device inoperative when thermally released, I prefer to provide means whereby the liquid will not be in contact with the outlet orifices until the device is put into actuation; 5 and a good and efficient device for bringing about this result is to extend the outlet pipes 123 and 123', around the receptacle wall within the same adjacent to the base, slightly less than half of the circumference, (Fig. 2) 10 so that when the device is suspended ready for use (Fig. 8) with what is the right side of Figs. 1 and 2 at the top, the level of the liquid in the receptacle will be as indicated by the line $f-f$ of Figs. 1 and 2, and when 15 in such position the pipe 123' having been drained of whatever liquid may have flowed into the same while being placed in position, etc., by merely forcing the stopper away from the nozzle, and then properly tensioning 20 its stopper-spring by turning the tension-screw 133, it will be seen that there will be no liquid at all in the pipe 123' and none in the pipe 123 adjacent to the nozzle; and yet that upon the release of the device 25 from the trip-cable 70, and its consequent rotation, both pipes will be instantly flooded, and the fluid directed out thru the same by the deflecting-vanes 95 and 95', which are usually and preferably of substantially the 30 curved shape clearly indicated in Fig. 2, so as to direct the liquid into the inner open ends of such pipes, as indicated at 96' of Fig. 2, and out thru the outer.

Secured to the peripheral wall of the 35 receptacle is a short stud-shaft 137 (Fig. 1), on which is vibratorily secured, usually by means of a screw 137', the closure carrying-ring actuating lever or rock-bar 136, in actuating connection with such ring at 40 the lower end and by means of a screw 138, passing thru a slot in such lever and screwing firmly into the adjacent spider securing-lug 110, and the ring 5'. The rock-bar 136 is provided at the top with the outwardly extending fork portion 135, in which slides 45 easily up and down the downwardly projecting lever actuating-lug 91, of the resilient spring trip-lever 26, vibratorily secured to the top of the receptacle B by means of the 50 pivot-stud or bolt 135'. This trip-lever 26 is normally held against its own resiliency in the raised position shown in full lines in Fig. 1, by the short quadrant-rail or stud 50' secured to the receptacle top; and when the 55 device is wound up and ready for actuation, the projecting contact portion 90 of such trip-lever 26 lies on what is the rear side of the frame A, in Fig. 1, behind the inwardly projecting corner trip-lug 90' formed 60 integral with the frame A, and in the position as indicated in full lines in Fig. 1, which shows the same as it is just about to contact with such trip-lug 90' after the receptacle has been put into rotation upon 65 the release of the thermo-trip G, and has

made nearly a complete revolution. As 90 comes into contact with 90' it is stopped and the receptacle continues to rotate, whereby the rock-bar 136 is vibrated so as to partially rotate the closure carrying-ring 5', 70 whereby the stoppers are removed from the outlet nozzles, as shown in dotted-lines in Fig. 6, and at this instant the lever 26 passing off from the rail or stud 50' such lever is by its own resiliency forced down into 75 the position shown in dotted lines (Fig. 1) so as to clear the trip-lug 90', after which such lever 26 will of course move with the receptacle.

Located near the top of the receptacle 80 adjacent to the upper end of the lever or rock-bar 136, is the combined filling and air-inlet orifice, which as shown in detail in Fig. 4, is usually provided with an outwardly screw-threaded bushing 139, soldered or brazed in position in the receptacle wall 7, on which is the washer 141, down on which is firmly screwed the inlet-cap 140, provided with the orifice 142, normally closed by the inlet-stopper 143, carried by the straight spring 144 secured to the lever 136, so that the vibration thereof will open the air-inlet orifice simultaneously with the opening of the outlet nozzles, upon the vibration of 136, as hereinbefore described. 95

For convenience in shipping filled, and in filling or refilling the receptacle the frame A is usually provided with three projecting feet or lugs indicated by 146 and 146', which together thus form practically a supporting 100 tripod at the side that is the left of Figs. 1 and 2, which lugs or feet may be formed integral with such frame, or secured thereto by screws 147.

The main support which allows the frame 105 A to gravitationally vibrate when released thermally, is preferably a flexible one, and in practice I have found a chain support 10, secured to a main supporting ring-bolt 10', affixed to the ceiling at the upper end, and to a supporting-ring 51' formed integral with the upper pivot-pin 51, to be highly efficient. In some cases, however, and where the device is of large size and consequent great weight, to avoid danger of breaking 110 the supporting chain as the same is twisted during the actuation of the device, a swivel-joint or link 9 (Fig. 1), is located therein of considerable retarding frictional power, sufficient to permit of the twisting up of the 115 chain so as to raise the device, and to thereafter swivel sufficiently to prevent the inertia of such heavy receptacle from breaking such chain; which swivel-joint or link 9, is preferably connected with the supporting-ring 120 and pintle-pin, as shown. And with the ordinary chain-swivels of commerce, I have found that while the same lessens it does not prevent wholly the twisting and untwisting of the chain during rotation, where- 125 130

by a consequent rising and falling, and gyroscopic pendulous motion is given to the entire device during operation, which results in equally distributing the contained liquid in 5 all directions surrounding the main suspension point 10' which will be itself deluged; whereby adjacent fire wherever located will be extinguished.

While the main-plate of the thermo-trip 10 G, shown in Fig. 1, which carries the rocking trip-lever 67 is usually located on what would be the rear side of the gyroscopic frame A, as shown in Fig. 1, and firmly 15 screwed in position by two suitable screw bolts passing thru the two holes shown in the bottom bar of the frame and screwing into such main plate, any other suitable means of securing such thermo-trip G in position may be used.

20 I do not intend to limit myself to the exact form of construction herein set forth, as many changes and modifications to adapt the device to particular uses may be made without departing from the scope of my invention; such for instance as changing the 25 shape or number or position of the outlet orifices, or of the air inlet orifices; and wherever I have in the claims hereof used the singular number in referring to any element, I intend 30 to cover and include thereby any desired plural number as well.

I claim:

1. In a device of the class described a receptacle adapted to contain a fire-extinguishing liquid aqueous-like fluent material provided with an outlet formed in and extending thru the peripheral wall thereof thru which the liquid may be expelled; and mechanical positive power means for simultaneously giving a plurality of liquid expelling motions to the receptacle.

2. In a device of the class described a receptacle adapted to contain a fire-extinguishing liquid aqueous-like fluent material provided with an outlet formed in and extending thru the peripheral wall thereof thru which the liquid may be expelled; and mechanical positive power means for simultaneously giving a plurality of liquid expelling motions to the receptacle, some of which are vibratory and others rotative in different varying planes.

3. In a device of the class described, a receptacle adapted to contain a fire-extinguishing liquid aqueous-like fluent material provided with a substantially cylindrical outlet thru which the liquid may be expelled; means for supporting the receptacle in such manner that the same may be pendulously vibrated; and means for simultaneously positively rotating the receptacle; whereby the liquid will be forcibly expelled and equally distributed in all directions.

4. In a device of the class described, a receptacle adapted to contain a fire-extinguish-

ing liquid aqueous-like fluent material, provided with an outlet formed in and extending thru the peripheral wall thru which such liquid will be ejected centrifugally upon the rotation of the receptacle; means within the 70 receptacle for causing the liquid to flow toward and out thru such outlet upon the rotation of the receptacle; motor-mechanism for causing rotation of the receptacle; and a thermo-trip normally locking the receptacle 75 against rotation.

5. In a device of the class described, a support; a receptacle adapted to contain a fire-extinguishing liquid aqueous-like fluent material revolvably carried by the support, and provided with a peripherally located outlet orifice thru which such liquid material will be expelled upon the rotation of the receptacle; closing means normally closing the outlet orifice, located on the 80 outer side of the receptacle at the outer end of such orifice; positive means for causing rotation of the receptacle relative to the support; a thermo-trip normally locking the receptacle against rotation but releasing the 85 same and permitting rotation upon the temperature of the surrounding atmosphere reaching a predetermined high point; and means for moving the outlet closing means into the open position upon the actuation of 90 the thermo-trip.

6. In a device of the class described, a support; a receptacle adapted to contain a fire-extinguishing liquid material revolvably carried by the support and provided with an 100 outlet thru which the fire-extinguishing liquid material will be centrifugally peripherally expelled upon rotation of the receptacle; closure means normally closing the outlet; positive power means for rotating the receptacle 105 relative to the support; a thermo-trip normally locking the receptacle against rotation but permitting rotation when thermally released; an air-inlet; closure means 110 normally closing the air-inlet; and means for causing the outlet and air-inlet closure means to be moved into the open position upon the rotation of the receptacle.

7. In a device of the class described, a support; a receptacle adapted to contain a 115 fire-extinguishing liquid material having an annular wall; an outlet-pipe extending around the annular wall adjacent thereto in communication at the inner end with the interior of the receptacle and with the exterior at the other end; a stopper normally closing the outlet pipe; means for rotating the receptacle; a thermo-trip normally locking the receptacle against rotation; and means for moving the outlet stopper into 120 the open position upon the thermal actuation of the thermo-trip, and consequent rotation of the receptacle.

8. In a device of the class described, a receptacle adapted to contain a fire-extin- 130

- guishing liquid material, such receptacle having an annular wall provided with an outlet orifice formed in and through the same; a closure normally closing the outlet orifice located at the outer end of such orifice outside of the receptacle wall; means for giving liquid expelling motion to the receptacle; a thermo-trip normally locking the receptacle against such motion until 10 thermally released; means for moving the outlet closure into the open position upon such fluid expelling movement of the receptacle, and means for keeping the liquid from contacting with the outlet orifice and its closure stopper while in the suspended and non-working position, and until the liquid expelling movement of the receptacle.
9. In a device of the class described, a receptacle adapted to contain a fire-extinguishing liquid material having an annular wall; an outlet pipe extending around the annular wall adjacent thereto within the receptacle and having its outlet extending out thru the wall; a deflecting vane within the receptacle for centrifugally forcing the liquid into the inner end of the outlet pipe upon the rotation of the receptacle; means for rotating the receptacle so as to cause expulsion of the liquid thru the outlet pipe; and 20 a thermo-trip normally locking the receptacle against rotation until thermally released.
10. In a device of the class described, a receptacle having an annular wall adapted to receive a fire-extinguishing liquid material; means for giving a liquid expelling rotary movement to the receptacle; a thermo-trip normally locking the receptacle against such rotation until thermally released; an outlet pipe adjacent to the annular wall of the receptacle the inlet orifice of which is located within the receptacle below the normal level of the contained liquid while the outlet orifice is located without the receptacle above such level; and a second outlet pipe in like communication with the exterior and interior of the receptacle save that its inlet orifice is above and its outlet below the normal level of the contained liquid until the thermal release and consequent rotation of the receptacle.
11. In a device of the class described, a receptacle adapted to contain a liquid aqueous like fire-extinguishing material, having an annular outer containing wall provided with an outlet formed in and extending thru the same; means for giving rotating content expelling motion to the receptacle; a thermo-trip normally locking the receptacle against such expelling movement until thermally released; and a deflecting-vane within the receptacle for centrifugally directing the contents toward and out thru the outlet upon the rotation of the receptacle.
12. In a device of the class described, a receptacle having an annular outer containing wall inclined inwardly toward the top and provided with an outlet adjacent to the base; a closure-stopper normally closing the outlet; a movable closure carrier supporting the closure-stopper; means for rotating the receptacle; a thermo-trip normally locking the receptacle against rotation until thermally released; and means for throwing the movable closure-carrier into the outlet opening position upon the actuation of the thermo-trip and movement of the receptacle.
13. In a device of the class described, a supporting frame; a receptacle revolvably supported by the frame; a cavity formed in the frame having peripherally located ratchet-stops; a pawl-carrying disk located in such cavity; a motor-spring-shaft; a motor-spring secured at one end to the motor-spring-shaft and at the other to the receptacle; means forming an actuating connection between the pawl-carrying-disk and the motor-spring-shaft; and means for rotating the pawl-carrying disk.
14. In a device of the class described, a receptacle adapted to receive a fire-extinguishing flowing material provided with an outlet thru which the same will be expelled upon rotation of the receptacle; a motor-spring shaft having a pivot-pin revolvably securing the receptacle in position; a motor-spring in actuating connection at one end with the receptacle and at the other with the motor-spring-shaft; a thermo-trip normally locking the receptacle against rotation; and a winding ratchet and pawl device for preventing rotation of the motor-spring-shaft except in the spring-winding-up direction in constant connection therewith.
15. In a device of the class described, a receptacle having an annular containing wall provided with an outlet thru the same of substantially circular contour in cross section; a closure normally closing such outlet; a movable closure carrying member supporting the closure; motor means for rotating the receptacle; a thermo-trip normally locking the receptacle against rotation; a trip-lever for actuating the movable closure carrying member; and means for causing movement of such trip-lever so as to throw the closure into the open position upon the release of the thermo-trip.
16. In a device of the class described, a receptacle having an annular containing wall provided with an outlet thru the same of substantially circular form in cross-section; a closure normally closing the outlet; a movable closure carrying member supporting the closure; motor means for rotating the receptacle; a thermo-trip normally locking the receptacle against rotation; a normally closed air-inlet leading to the interior of the receptacle; and a trip-mechanism for bring-

ing about the opening of the outlet and the inlet upon the actuation of the thermo-trip, and the consequent rotation of the receptacle.

5 17. In a device of the class described, a supporting-frame; a receptacle revolubly supported by the frame; means for positively rotating the receptacle relative to the supporting-frame; a thermo-trip normally 10 locking the receptacle against rotation; and means for normally positioning the receptacle whereby the outlet or outlet orifices and the movable stoppers normally closing the same will have none of the contained 15 aqueous-like fire-extinguishing material in contact therewith.

18. In a device of the class described, a receptacle having an annular peripheral wall; an outlet formed in and extending 20 thru the wall; a closure normally closing the outlet; a moving member for moving the closure; a spring normally yieldingly holding the closure in the closed position; means for varying the tension of the spring; means 25 for rotating the receptacle; a thermo-trip normally locking the receptacle against rotation; a trip-lever for actuating the moving member; and means for causing actuation 30 of the trip-lever upon the thermal release of the thermo-trip.

19. In a device of the class described, comprising a receptacle adapted to contain an aqueous-like fluent liquid fire-extinguishing material, having an outlet orifice or orifices 35 in the peripheral wall, located adjacent to the base end of the receptacle; a gyroscopic-frame revolubly supporting the receptacle therein; a normally tensioned coiled motor-spring releasably connected at one end with 40 the receptacle adapted to put the receptacle into rotation, and to be automatically released from the receptacle when it reaches the limit of its throw; a thermo-trip normally 45 locking the receptacle and coiled motor-spring against movement; outlet closure mechanism normally closing the outlet or outlets; mechanism for moving the outlet closure-mechanism into the outlet opening position upon the rotation of the receptacle; 50 a vibratory main-support secured to one end portion of the gyroscopic-frame; and an auxilliary support secured to the end portion of the gyroscopic-frame substantially 55 opposite to that to which such main-support is attached, in such manner as to be released from the gyroscopic-frame upon the actuation of the thermo-trip, whereby the gyroscopic-frame and contained receptacle will 60 be pendulously gravitationally vibrated upon such thermal release.

20. A fire extinguisher having the characteristics set forth and enumerated in claim 1, also comprising that of automatic release 65 of the receptacle from the rotating mechanism after a predetermined number of ro-

tations, so as to allow the receptacle to spin from its own inertia following the initial impulse.

21. A fire extinguisher having the characteristics set forth and enumerated in claim 70 2, also comprising that of automatic release of the receptacle from the rotating mechanism after a predetermined number of rotations, so as to allow the receptacle to spin from its own inertia following the initial 75 impulse.

22. A fire extinguisher having the characteristics set forth and enumerated in claim 80 3, also comprising that of automatic release of the receptacle from the rotating mechanism after a predetermined number of rotations, so as to allow the receptacle to spin from its own inertia following the initial 85 impulse.

23. A fire extinguisher having the characteristics set forth and enumerated in claim 85 4, also comprising that of automatic release of the receptacle from the rotating mechanism after a predetermined number of rotations, so as to allow the receptacle to spin 90 from its own inertia following the initial impulse.

24. A fire extinguisher having the characteristics set forth and enumerated in claim 95 5, also comprising that of automatic release of the receptacle from the rotating mechanism after a predetermined number of rotations, so as to allow the receptacle to spin 100 from its own inertia following the initial impulse.

25. A fire extinguisher having the characteristics set forth and enumerated in claim 105 6, also comprising that of automatic release of the receptacle from the rotating mechanism after a predetermined number of rotations, so as to allow the receptacle to spin from its own inertia following the initial impulse.

26. A fire extinguisher having the characteristics set forth and enumerated in claim 110 7, also comprising that of automatic release of the receptacle from the rotating mechanism after a predetermined number of rotations, so as to allow the receptacle to spin 115 from its own inertia following the initial impulse.

27. A fire extinguisher having the characteristics set forth and enumerated in claim 120 8, also comprising that of automatic release of the receptacle from the rotating mechanism after a predetermined number of rotations, so as to allow the receptacle to spin from its own inertia following the initial impulse.

28. A fire extinguisher having the characteristics set forth and enumerated in claim 125 9, also comprising that of automatic release of the receptacles from the rotating mechanism after a predetermined number of rotations, so as to allow the receptacle to spin 130

from its own inertia following the initial impulse.

29. A fire extinguisher having the characteristics set forth and enumerated in claim 5 10, also comprising that of automatic release of the receptacle from the rotating mechanism after a predetermined number of rotations, so as to allow the receptacle to spin from its own inertia following the initial 10 impulse.

30. A fire extinguisher having the characteristics set forth and enumerated in claim 11, also comprising that of automatic release of the receptacle from the rotating mechanism after a predetermined number of rotations, so as to allow the receptacle to spin from its own inertia following the initial 15 impulse.

31. A fire extinguisher having the characteristics set forth and enumerated in claim 20 12, also comprising that of automatic release of the receptacle from the rotating mechanism after a predetermined number of rotations, so as to allow the receptacle to spin 25 from its own inertia following the initial impulse.

32. A fire extinguisher having the characteristics set forth and enumerated in claim 15, also comprising that of automatic release 30 of the receptacle from the rotating mechanism after a predetermined number of rota-

tions, so as to allow the receptacle to spin from its own inertia following the initial impulse.

33. A fire extinguisher having the characteristics set forth and enumerated in claim 16, also comprising that of automatic release of the receptacle from the rotating mechanism after a predetermined number of rotations, so as to allow the receptacle to spin 40 from its own inertia following the initial impulse.

34. A fire extinguisher having the characteristics set forth and enumerated in claim 17, also comprising that of automatic release 45 of the receptacle from the rotating mechanism after a predetermined number of rotations, so as to allow the receptacle to spin from its own inertia following the initial 50 impulse.

35. A fire extinguisher having the characteristics set forth and enumerated in claim 18, also comprising that of automatic release 55 of the receptacle from the rotating mechanism after a predetermined number of rotations, so as to allow the receptacle to spin from its own inertia following the initial impulse.

Signed at the city, county, and State of New York, this 21st day of July, 1919.

CLARENCE LADD-DAVIS.
